UNITED STATES PATENT OFFICE

2,443,800

TRUSS

Benjamin F. Pease, Worcester, Mass.

Application February 22, 1944, Serial No. 523,404

2 Claims. (Cl. 128—99)

1

This invention relates to improvements in trusses and particularly to spring frame trusses and to an improved back pad therefor.

The present invention includes an improvement on the subject matter of my former invention disclosed in U. S. Letters Patent No. 1,956,299, dated April 24, 1934.

Objects of the invention are to provide a truss of simple, economical construction which will be strong and durable and which includes a back pad having a rear face offset forwardly particularly along the entire lower portion thereof with the main upper portion of said rear face bulged outwardly, and to provide said forwardly offset portion with screws or studs or other fastening means for adjustably connecting a strap to said pad whereby the strap will lay flat on said offset area without objectional bulge, and the outwardly bulged portion of said rear face will protect the clothing from undue wear by being brought into forced contact with said fastening means.

A particular object is to provide a truss having spring side members connected at the forward ends thereof to a yoke arranged to have mounted thereon holding means for a hernia pad, and said side members oppositely curved to extend around a portion of the body, and to provide a padded sheath covering each side member, the rearwardly presented ends of which are enlarged and have inserted therein a plate with means to detachably secure the rearwardly presented end of each side member to one of said plates to form a highly efficient back pad.

In the drawings there is shown an illustrative embodiment of the invention, it being understood that the invention is not confined to the exact form shown and that changes and modifications may be made which come within the scope of the claims hereinafter set forth.

In the drawings:

Figure 1 is a perspective view of a truss constructed in accordance with this invention, the same being taken from the rear side thereof.

Figure 2 is a cross-sectional view taken as indicated by the line 2—2 of Figure 1.

Figure 3 is a plan view of the rear side of a plate employed to reinforce said pad.

Figure 4 is a cross-sectional view taken as indicated by the line 4—4 of Figure 1.

In the particular adaptation of the invention shown in the drawings, the reference character 5 denotes a yoke forming the forward part of the truss. The yoke 5 is provided with slots 6 for attaching a hernia pad or pad holding means

thereto. Flat arcuate spring side members 7 or 8 are riveted, bolted or otherwise secured to the yoke 5. The members 7 and 8 are oppositely positioned to extend around the body with the rear ends thereof presented toward each other.

The numeral 9 denotes a sheath having an outer wall 10 and an inner wall 11 enclosing a longitudinally extending cavity 12 for receiving a side member 7 or 8. The inner wall 11 is composed of a soft pliable layer 11a, a relatively stiff layer 11b with cotton, hair or other padding material positioned therebetween. The sheaths 9 are enlarged at the rear ends thereof to form a back pad as hereinafter described. Each sheath 9 is open at the forward end thereof with the enlarged rear end closed.

A plate 15 composed of sheet metal or other relatively stiff material is shaped to conform to the desired contour of the back pad hereinafter described. In the adaptation of the invention shown in the drawing, the plate 15 has a relatively wide rounded end portion 15a tapering to a relatively narrow end 15b. The plate 15 is stamped forwardly from the rearwardly presented side thereof to form a depressed seat 16 which extends therein from the narrow end 15b thereof and is disposed in spaced relation to the upper edge thereof. The seat 16 has an outline corresponding to the end portion of the adjacent side member, 7 or 8 which fits therein.

The entire lower portion 15c of the plate 15 is offset forwardly to extend in a plane spaced forwardly from the plane of the rear face of the upper portion 15d of the plate. The upper portion 15d is preferably bulged rearwardly with the edges thereof curved forwardly to the plane of the lower portion 15d.

A plate 15 is positioned in the cavity 12 of the enlarged end portion of each sheath 9. One of the side members 7 or 8 is entered through the open end of each sheath 9 and is positioned therein with the rear end thereof entered in the seat 16. Each side member 7 or 8 is provided with apertures which coincide with threaded bores 17 in the plate 15 and suitable screws 19 are entered through apertures in the rear wall 10 and through the apertures in said side members and are operatively secured in the threaded bores 17 to securely hold the sheaths 9 on the side arms 7 and 8.

As shown in the drawing, the seat 16 is of sufficient depth to position the head of the screws 19 forwardly of the rear face of the upper portion 15d. The outer wall 10 being formed of leather or other flexible material, readily con-

forms to the contours of the rear face of the plate 15.

A stud 20 having a threaded shank 21 is positioned through an aperture in the wall 10 and operatively positioned in a threaded bore 18 in the forwardly offset portion 15c of the plate 15. The stud 20 has a head 22 which is spaced forwardly from the plane of the upper portion 15d.

A strap 25 is provided with a longitudinally extending row of spaced holes 26. The strap 25 is positioned flat against the forwardly offset portions 15c and the studs 20 are entered in the holes 26 to connect the rear ends of the truss. It will be seen that the strap 25 may be adjustably secured to the back pads thus formed, and may extend beyond the pads without objectional bulge, and that both the strap 25 and studs 20 will be held out of forced contact with the clothing by the outwardly bulged upper portion 15d.

While I have shown a pad formed by the sheath 9 and plate 15, it is to be understood that the pad portion may be molded in one piece or otherwise formed to present a rear face having a similar arrangement of surfaces.

Having thus illustrated my invention and described the same in detail, what I claim as new and desire to secure by Letters Patent is:

1. In a truss of the character described and having a connecting strap, in combination, a back pad having a transversely extended rear member depressed and offset forwardly along the

entire length of the lower extended edge portion thereof, and means projecting rearwardly from said depressed lower portion and to which the connecting strap may be attached, and said latter means being wholly below the rear surface of said pad.

2. In a truss of the character described, a frame having end portions terminating in spaced relation at the back of the truss, a back pad on each end portion having a substantially rigid rear member, said rear member for each pad having a lateral extension which is depressed and offset forwardly along its entire circumferential length, a strap connecting said pads and extending lengthwise along said lateral extension, and means on the depressed and offset lateral extension of one of said rear members for detachably securing the strap thereto.

BENJAMIN F. PEASE.
